UNITED STATES PATENT OFFICE.

FREDERICK A. STAFFORD, OF CHARITON, IOWA.

MASONRY STRUCTURE.

1,186,501.

Specification of Letters Patent.

Patented June 6, 1916.

Application filed July 12, 1915. Serial No. 39,484.

To all whom it may concern:

Be it known that I, FREDERICK A. STAFFORD, a citizen of the United States, and resident of Chariton, in the county of Lucas and State of Iowa, have invented a certain new and useful Masonry Structure, of which the following is a specification.

The object of my invention is to provide a masonry structure of simple, durable and inexpensive construction.

A further object is to provide a masonry structure made up of blocks each having a longitudinally reinforcing member, having at its opposite ends an eye, and a substantially upright member, the blocks being provided with notches to receive the eye and upright member, a portion being so arranged as to permit, particularly in a circular structure, the upright member to be received in the eye in such a way that the blocks may be laid end to end in a course, and the reinforcing members may, if desired, be connected so as to impose initial tension on the blocks in the course without the use of any additional tools or parts, either for fastening the reinforcing members on the opposite blocks together, or for changing their form after the blocks are set.

My invention consists in the construction, arrangement, and combination of the various parts of the device, whereby the objects contemplated are attained as hereinafter more fully set forth, pointed out in my claim, and illustrated in the accompanying drawings, in which:

Figure 1 shows a top or plan view of a portion of a masonry course in the structure embodying my invention. Fig. 2 shows a side elevation of one of the blocks, and Fig. 3 shows a side elevation of a part of a masonry structure embodying my invention, the upper portion of the blocks being shown in vertical section along the line of reinforcement.

In the accompanying drawings, I have used the reference numeral 10 to indicate generally a block made of any suitable plastic material, such, for instance, as concrete, which block is comparatively thin from front to back, as shown. The block may be of any desired shape, length, thickness and height, and may be curved on the arc of a circle of the structure in which the block is to be used, as illustrated in Fig. 1. Each block is provided at each end near its up-

per portion with a notch or slot 11. The slots 11 are somewhat exaggerated in the drawings, in order to show the parts clearly. These are preferably made just large enough to permit the reinforcing elements in the adjacent blocks in a course of masonry structure to be connected. Near the upper surface of each block 10 is laid a longitudinally arranged reinforcing member 12 which may be a rod as shown. At one end of each rod is formed an eye or loop 13 and at the other end of each rod is an upwardly inclined member 14, preferably also inclined somewhat away from the block, as illustrated in Fig. 2.

The rod may be slightly inclined from the horizontal, or the ends of the reinforcing members in the slots may be slightly bent, so that the end of the member having the eye is inclined slightly upwardly, as at 15 in Fig. 3, while the end of the member having the upwardly inclined member 14 is inclined slightly outwardly as at 14 in said Fig. 3, for the more convenient connecting of the parts. The blocks are laid in superposed courses in broken joints in the ordinary way.

After one block in the course has been laid, the next block is placed in position preferably with mortar joints, which, however, forms no particular part of my present invention. The blocks are placed end to end with one block having its end with the eye adjacent to the end of another block 90 having the upwardly inclined portion 14. The block A, for instance, in the course is laid in position, then the block B, as shown clearly in Fig. 3, is placed in position, and may be tilted slightly, if necessary, to 95 bring the eye 13 over the upwardly inclined member 14. Mortar may be placed in the lower part of head joint, and it will be seen that on this account and on account of the inclination of the member 14 away 100 from the block with which it is connected, as the block B slides downwardly, a tension will be imposed upon the reinforcing members 12 without the use of tools, and without any particular manipulation of the reinforcing members. This tension will be continued around the entire course. If desired the portions 14 may be bent over with a hammer, a piece of pipe, or any suitable tool.

When it comes to the last member of the course, the end of the block having the up-

wardly inclined member 14, is placed adjacent to the end of the block having the eye which is already laid, and the block to be laid is tilted upwardly, while the member 14 is placed just below the eye. The block to be laid is then swung downwardly and the member 14 will move into the eye 13 while the eye 13 of the block to be placed will drop over the member 14 on the first block of the adjacent block in the row.

The laying of the blocks in mortar will cause the notches 11 to be filled with plastic material, which may be as rich as desired, so that all reinforcing will be fully protected from the weather. A very strong mortar joint will be provided in which the rich moisture extends into both the adjacent blocks and surrounds and joins the connecting reinforcing members. Superposed tension is imposed upon the blocks in the circular course, and a rigid thoroughly reinforced structure is produced.

It will be understood that some changes may be made in the construction of my masonry structure without departing from its essential features and purposes, and it is my intent to cover by this application any such changes which may be included within the scope of my claim.

I claim as my invention.

In a masonry structure, a wall composed of blocks arranged in superposed courses, with the blocks of the adjacent courses staggered with relation to each other, each block having in its upper surface, at its ends, comparatively shallow recesses, each block having in its upper portion a longitudinally arranged reinforcing member, the ends of which project into said recesses, one

end of each reinforcing member having 40 formed thereon a horizontal loop or eye, the other end having an upward extension, the parts being so arranged that when a block has been placed in a course, the next block may be laid into position endwise with the 45 first block, and with the loop or eye of the reinforcing member of one block receiving the upward extension of the reinforcing member of the other block substantially on a line between the blocks, and at such a 50 point as to be convenient of access with a tool or the like from above the course, the parts being so arranged that by filling the recesses, between the adjacent blocks in a 55 course, the reinforcing members may be entirely covered with plastic material, the projecting ends of the reinforcing members, at the opposite ends of each block, being arranged in slightly different horizontal planes with the loops or eyes slightly above 60 the level of the ends having the upward extensions, so that when the blocks are arranged in a course end to end, the reinforcing members may be easily connected without interfering with placing the blocks in 65 level position, the upwardly extending portions and the loops or eyes of the blocks being so arranged with relation to the ends thereof and the upwardly extending portions being so inclined, that when the 70 blocks are assembled together end to end, initial strain is imposed on the reinforcing.

Des Moines, Iowa, July 6, 1915.
